UNITED STATES PATENT OFFICE

165,227

PYROPHORIC LIGHTER

André Léandre Guenin, Geneva, Switzerland, assignor to La Nationale S. A., Geneva, Switzerland, a corporation of Switzerland

Application August 9, 1950, Serial No. 11,685
In Switzerland April 22, 1950

Term of patent 14 years

(Cl. D48—27)

To all whom it may concern:

Be it known that I, André Léandre Guenin, a citizen of Switzerland, and resident of Geneva, Switzerland, have invented a new, original, and ornamental Design for a Pyrophoric Lighter, of which the following is a specification, reference being had to the accompanying drawing, forming part thereof.

Fig. 1 is a perspective view of a pyrophoric lighter showing my new design, seen from its front face;

Fig. 2 is a perspective view of the rear face of the lighter.

I claim:

The ornamental design for a pyrophoric lighter, as shown.

ANDRÉ LÉANDRE GUENIN.
